(57) **CLAIM**

The ornamental design for footwear insole, as shown and described.

DESCRIPTION

FIG. 1 is a perspective view of the footwear sole embodying the new design.

FIG. 2 is a top plan view thereof.

FIG. 3 is a right side view thereof.

FIG. 4 is a left side view thereof.

FIG. 5 is a rear view thereof; and,

FIG. 6 is a front view thereof.

FIGS. 1–6 show features of an article of footwear in phantom lines. These features are shown for environmental purposes and do not form any part of the claimed design.
